UNITED STATES PATENT OFFICE.

VICTOR M. VILLEMAIN, OF NEW YORK, N. Y.

DESIGN FOR A COMBINATION KNIFE, FORK, SPOON, AND TOOTHPICK.

47,443.

Specification for Design.

Patented June 8, 1915.

Application filed November 4, 1914. Serial No. 870,309. Term of patent 14 years.

To all whom it may concern:

Be it known that I, VICTOR M. VILLEMAIN, a citizen of the United States, residing at New York city, in the county and State of New York, have invented a new, original, and ornamental Design for a Combination Knife, Fork, Spoon, and Toothpick, of which the following is a specification, reference being had to the accompanying drawing, forming part thereof.

Figure 1 is a plan view of the design.
Fig. 2 is a side elevation of the design.

I claim:—

The ornamental design for a combination knife fork, spoon and toothpick, as shown.

VICTOR M. VILLEMAIN.

Witnesses:

GEO. A. BYRNE,
M. E. LAUGHLIN.
